[57] CLAIM

The ornamental design for a wrist and arm support, as shown and described.

DESCRIPTION

FIG. 1 is a perspective view of my new wrist and arm support with a phantom line showing of a computer mouse detachably attached to the bottom thereof to show the environment of use;

FIG. 2 is a top plan view thereof;

FIG. 3 is a right side elevational view thereof, the left side elevational view being identical thereto;

FIG. 4 is a bottom plan view thereof;

FIG. 5 is a front elevational view thereof; and,

FIG. 6 is a rear elevational view thereof.
